[57] CLAIM

The ornamental design for wristwatch strap, as shown and described.

DESCRIPTION

FIG. 1 is a top plan view in extended form of my improved wristwatch strap;

FIG. 2 is a left side elevational view thereof;

FIG. 3 is a right side elevational view thereof;

FIG. 4 is a bottom plan view thereof;

FIG. 5 is an elevational view of the tab end thereof; and,

FIG. 6 is an elevational view of the buckle end thereof.

The watchcase, which is shown in dashed lines in FIGS. 1-4, is not part of the design.
